CLAIM

The ornamental design for a electronic module holder for package tracking and monitoring, as shown and described.

DESCRIPTION

FIG. 1 is a perspective view of my new design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot dash dot lines immediately adjacent to the shaded areas represent bounds of the claimed design while all other broken lines are included for the purpose of illustrating portions of the electronic module holder for package tracking and monitoring; the broken lines form no part of the claimed design.
